RELAY

Oscar S. Field, Rochester, N. Y., assignor to
General Railway Signal Company, Rochester,
N. Y.

Application November 1, 1932. Serial No. 640,698

8 Claims. (Cl. 175—336)

This invention relates to relays and more particularly to a direct current type of relay adapted for use in railway signalling.

The usual type of relay used in railway signalling practice employs an armature which is operable about pivot pins or trunnions. Under ordinary conditions the bearing provided by these trunnions permits a free movement of the armature therein, but it has been found that when such armature pivoting arrangements are exposed to the atmosphere of certain localities, sufficient corrosion will take place to greatly increase the friction of the pivot bearing. The railway signalling circuits employing these relays are so arranged that the safety of train movements is dependent on the dropping of the armature after a reduction or an interruption of the energy applied to the armature operating means, and consequently any increase in resistance caused by such corrosion may prevent the gravitational movement of the armature to its de-energized position thereby greatly endangering traffic movements by effecting a false clear indication.

In view of the above and other considerations, it is proposed in accordance with the present invention to construct a relay having an armature supporting means which permits free operating movement of the armature, and yet which is substantially not affected by corrosion and in which wear and friction in operation is entirely eliminated. It is also proposed to provide such a supporting means which holds the armature in a manner assuring a particular operating relation relative to the operating means regardless of the position of the relay, and in which, such supporting means is conveniently adjustable to obtain uniform and accurate operating characteristics.

Other objects, purposes and characteristic features of the present invention will appear as the description thereof progresses, during which references will be made to the accompanying drawings, in which:

Fig. 1 is a sectional side elevational view of a relay constructed in accordance with the present invention.

Fig. 2 is a sectional plan view taken substantially on line 2—2 of Fig. 1 and viewed in the direction indicated by the arrows.

Fig. 3 is an end elevational view of a section taken substantially on line 3—3 of Fig. 1 showing the armature in its attracted position.

Fig. 4 is a view of Fig. 3 showing the armature in its unattracted position.

Fig. 5 is an exploded perspective view of the

present invention shown in a simplified manner to illustrate the operation thereof.

The armature supporting means proposed in accordance with the present invention is shown for convenience in the accompanying drawings as 60 replacing the trunnion arrangement of such a relay as disclosed in the patent to O. S. Field No. 1,824,129 dated September 22, 1931, but it is to be understood that this arrangement may similarly be applied to any relay having a tractive type 65 armature. The construction of this particular relay may be clearly understood by referring to the above patent, and consequently a very brief description of this portion of the drawings will be considered sufficient. 70

Referring to the accompanying drawings, the essential parts of the relay are mounted on an insulating top member 1 which holds two magnetic cores 2 and 3 having enlarged pole pieces 2¹ and 3¹ which are secured to the insulating member 1, such as by screws not shown herein. The cores 2 and 3 carry coils 4 and 5 respectively, and the magnetic circuit between the cores is closed at the top by yokes of magnetic material which are not shown herein but are fully shown 80 and described in the above mentioned patent. An armature 6 is supported as later described so as to be attractable against the pole faces 2¹ and 3¹ by the energization of the coils 4 and 5, and the armature 6 is biased by gravity to a lower position shown in Fig. 4 when the coils are de-energized. It is to be understood that a plurality of contacts of any suitable type may be mounted on the armature 6 but only a single contact finger 26 has been shown as mounted thereon by insulating 85 connectors 27 which hold inserted metallic screws 28 threaded into the armature 6 (see Fig. 1) and insulated metallic screws 29 which hold the contact finger 26 by nuts 30. In order to simplify the disclosure, the fixed contacts associated with the contact finger 26 are conveniently shown as a front point 30' and a back point 31. The lower part of the relay may be enclosed by a glass cover 32 which is held against the top insulating member by means not shown. 90

An armature supporting member 8 which is substantially U-shaped, as shown in Fig. 2, is held on each side to the top insulating member 1 by screws 9 and 10 passing through elongated holes 33 in the member 8. The legs of the U-shaped armature supporting member 8 which extend along the outside of the pole pieces 2' and 3' are bent downwardly to form feet 11 and 12 which are shaped as shown in Fig. 3, and a brace 13 is riveted to the ends of the downwardly ex- 105 110

tending feet 11 and 12 with the center portion of the brace 13 fixed to the central portion of the armature supporting member 8 by rivets 14.

Two brackets 17 and 18 are riveted to opposite ends of the armature 6 and extend to the rear of the pole pieces 2¹ and 3¹ where rectangular shaped ends 17¹ and 18¹ extend outwardly at right angles thereto, which may be clearly seen in Fig. 5. Vertical flexible strips 21 and 22 are fixed at their upper ends to the rectangular armature bracket portions 17¹ and 18¹ respectively by rivets 19, and the lower ends are held by rivets 20 between the brace 13 and the feet 11 and 12 respectively by rivets 20. Horizontal flexible strips 23 and 24 also connect the armature 6 to holding member 8 outside the vertical strips 21 and 22 and are held at one end to their respective rectangular bracket portions 17¹ and 18¹ by rivets 16 and the other end is held to their respective armature holding legs 11 and 12 by rivets 15. These flexible strips 21, 22, 23 and 24 are of thin spring material, such as phosphor bronze, and of a predetermined width and thickness which will rigidly support the armature and yet have sufficient lateral flexibility to allow a slight movement of the armature relative to the pole pieces 2¹ and 3¹.

The armature supporting member 8 is adjustably mounted on the screws 9 and 10 by upper nuts 34 and lower nuts 35 which obviously permit vertical adjustment of the member 6 on the screws 9 and 10 whereby the air gap between the pole pieces 2¹ and 3¹ may be varied. A slight horizontal adjustment of the armature supporting member 8 is also permitted by the elongated holes 33 (see Fig. 2) through which the screws 9 and 10 pass thereby allowing the armature to be accurately positioned beneath the pole pieces 2¹ and 3¹.

40 The arrangement of the flexible armature mounting strips is more clearly shown in the perspective view of one side of the armature shown in Fig. 5, and when such an arrangement is applied to each side of the armature, it will be obvious that the armature is pivotally operable relative to the pole pieces about what may be termed a phantom pivot point located at the crossing point of the horizontal and vertical flexible strips. It is obviously necessary for operation of the armature to locate the vertical flexible strips in laterally spaced relation to the vertical axis of the operating electro-magnets, and it is further obvious that the horizontal flexible strips are necessary to maintain a definite operation of the armature because otherwise the armature might shift horizontally due to vibration or other causes and vary the operating characteristics due to the indefinite relation between the pole pieces and armature or between the fixed and movable contacts.

45 A relay armature supporting means has thus been provided which permits non-frictional operation of the armature and in which the resistance offered to such operation is constant and not affected by rust or corrosion which may prevent operation of an armature supported by a frictional armature pivoting means. An important feature of the present invention is the use of both horizontal and vertical flexible armature 50 mounting strips which provide a stable armature support comparable with that obtained from frictional pivots, such as trunnions. A means for adjusting the position of an armature thus supported has also been provided which enables the 55 armature to be accurately positioned relative to

the operating means in both horizontal and vertical planes whereby a relay having uniform and accurate operating characteristics may be obtained.

80 The above rather specific description of one form of the present invention is given solely by way of example, and is not intended, in any manner whatsoever, in a limiting sense. It is also to be understood that various modifications, adaptations and alterations may be applied to meet the 85 requirements of practice, without in any manner departing from the spirit or scope of the present invention, except as limited by the appended claims.

Having thus shown and described my invention, 90 what I claim is:—

1. In a relay, a vertical electro-magnet having horizontally spaced pole pieces, a frame, an armature, horizontal spring strips connecting the armature and said frame whereby the armature is maintained in a definite horizontal relation to said pole pieces, and vertical spring strips connecting said frame and points on said armature spaced horizontally from the axis of said electro-magnets whereby said armature is 100 pivotably movable relative to said pole pieces by lateral flexion of said horizontal and vertical spring strips.

2. In a relay, an insulating base member, an electro-magnet mounted above said base member and having pole pieces projecting beneath the base plate, an armature, an armature supporting member, adjustable means for mounting said armature supporting member to said base member, spaced brackets extending laterally 105 from said armature, horizontal and vertical spring strips connecting said brackets and said armature supporting member to hold said armature beneath said pole pieces whereby said armature is operable relative to said pole pieces by 110 lateral bending of said spring strips.

3. In a relay, a supporting member, an electro-magnet mounted on said supporting member, an armature, an armature holding member, an adjustable means for mounting said armature holding member on said supporting member, a pair of spaced laterally flexible members connecting said armature to said armature holding member and extending substantially at right angles to the line of traction of said electro- 125 magnet, and a second pair of spaced laterally flexible members connecting said armature to said armature holding member and extending substantially parallel to but spaced laterally from the line of traction of said electro-magnet. 130

4. In a relay, in combination, an electro-magnet, an armature, an armature holding member, spaced screws extending from said electro-magnet, adjustable means for mounting said armature holding member at various points along the 135 extending portion of said screws, a pair of spaced flexible strips connecting said armature to said armature holding member, and a second pair of spaced flexible strips connecting said armature to said armature holding member but angularly 140 disposed with respect to said first pair of flexible strips.

5. In a relay, in combination, an electro-magnet, an armature, spaced screws extending from said electro-magnet, an armature holding member having elongated holes receiving said screws, adjustable means for mounting said armature holding member at various points along the extending portion of said screws and permitting adjustment of said armature holding member by 150

the elongated holes therein in a plane substantially at right angles to the axis of said screws, a pair of spaced flexible strips connecting said armature to said armature holding member, and 5 a second pair of spaced flexible strips connecting said armature to said armature holding member but angularly disposed with respect to said first pair of flexible strips.

6. In a relay, an electro-magnet, an armature, 10 a first and a second pair of flexible strips holding said armature in operable relation to said electro-magnet, said second pair of flexible strips being angularly disposed relative to said first pair of flexible strips whereby to form a virtual pivot 15 for said armature.

7. A relay comprising an electro-magnet, an armature, and a non-frictional spring means including a plurality of angularly positioned spring strips each rigidly fixed to the armature for forming a virtual pivot for holding said armature 80 in operable relation to said electro-magnet.

8. In a relay, in combination with an electro-magnet, an armature, an armature holding member, a pair of spaced flexible strips connecting said armature to said armature holding member, 85 and a second pair of spaced flexible strips connecting said armature to said armature holding member and angularly disposed with respect to said first pair of flexible strips.
